UNITED STATES PATENT OFFICE

2,325,286

PROTECTOR MECHANISM FOR LOOMS

Grover C. Tarte, Blackstock, S. C.

Application April 29, 1942, Serial No. 441,011

5 Claims. (Cl. 139—345)

My invention relates to looms and has particular reference to stopping mechanism for the same:

An important object of the invention is to provide loom stopping mechanism of the protector-rod type having means whereby either end portion may be readily removed without disturbing the other end portion:

A further object of the invention is to provide means whereby the intermediate portion of the protector-rod may be removed without disturbing the end portions:

A further object of the invention is to provide means of the above-mentioned character which will engage with the protector-rod bearings and hold the protector-rod against longitudinal displacement:

A further object of the invention is to provide means whereby the spring of the protector-rod may be quickly and conveniently adjusted or placed under tension, or removed:

A further object of the invention is to provide means of the above-mentioned character which is simple in construction and cheap to manufacture:

Other objects and advantages of the invention will be apparent during the course of the following description.

In the accompanying drawing forming a part of this application and in which like numerals are employed to designate like parts throughout the same,

Figure 1 is a front elevation of the lay of the loom and associated elements having my invention applied thereto;

Figure 2 is a transverse section taken on line 2—2 of Figure 1;

Figure 3 is a plan view of my improved protector-rod;

Figure 4 is a transverse section taken on line 4—4 of Figure 3;

Figure 5 is a similar view taken on line 5—5 of Figure 3;

Figure 6 is a perspective view of an intermediate bearing for the protector-rod; and,

Figure 7 is a perspective view of one of the coupling-sleeves.

In the drawing, wherein for the purpose of illustration is shown a preferred embodiment of my invention, the numeral 10 designates the lay of a conventional loom, supported by vertically swinging swords 11 pivotally mounted upon a lower rocker-shaft 12. The lay 10 extends outwardly beyond the swords 11 and carries shuttle boxes 13. These shuttle boxes are equipped with

the usual pivoted spring-pressed binders 14, which are moved outwardly by the shuttle when it enters the shuttle box. This binder 14 may be of the type shown in Patents 1,807,735 and 628,893.

In the conventional loom, means is provided to stop the stroke of the lay if such stroke is started when the shuttle is not in either shuttle box so that it cannot move the binder to the outer position. The present invention provides an improved stopping means for accomplishing this purpose. This means includes a protector-rod 15 formed in separate outer protector-rod sections 16 and an intermediate protector-rod section 17. The protector-rod sections 16 are journaled in bearings 18, arranged beneath the lay 10 and secured to the front side of the swords 11 by bolts 19. The intermediate protector-rod section 17 is arranged between the inner ends 19 of the protector-rod sections 16 and the ends 20 of the intermediate protector-rod section 17 are permanently spaced from the ends 19 for a considerable distance. I prefer to provide a space of about three inches although this may be varied. Coupling-sleeves 21 are provided to slidably receive the inner ends of the protector-rod sections 16 and the outer ends of the intermediate protector-rod section 17. The coupling-sleeves 21 are clamped to the protector-rod sections 16 by set screws 22 and the coupling-sleeves are also clamped to the intermediate protector-rod section 17 by set screws 23. It is thus seen that the coupling-sleeves serve to normally rigidly connect the end protector-rod sections 16 and the intermediate protector-rod section 17 so that they turn as a unit. The coupling-sleeves 21 are provided at their outer ends with flanges or bosses 24, preferably formed integral therewith and these bosses slidably engage the ends of the bearings 18, serving to prevent perceptible longitudinal play of the protector-rod 15 and also serving as washers.

Rigidly secured to the outer ends of the protector-rod sections 16 are horizontal extensions or cranks 25, which may be formed integral therewith and these cranks carry upstanding fingers 26 also preferably formed integral with the cranks. The fingers 26 are arranged upon the rear side of the lay 10 and are disposed to permanently engage with the binders 14. These fingers are swung to the front to be retained in engagement with the binders by a torsional coil spring 27, surrounding the intermediate protector-rod section 17. One end of this spring is hooked at 28 to engage over the flange 29 of a

bearing 30 and this bearing is rigidly attached to the lay by a bolt 30'. The other end of the spring is preferably straight as shown at 31 and is adapted for insertion within a selected opening 32, formed in a flange 33 formed upon a collar 34. For convenience of manipulation there are a plurality of these openings 33. The collar is clamped to the protector-rod section 17 by a plurality of set screws 35 to engage within openings 36. It is obvious that the collar may be turned to place the spring under tension and then clamped to the protector-rod section 17.

Arranged upon the outer sides of the swords 11 and extending to the front side of the lay are daggers 37, rigidly secured to the protector-rod sections 16. These daggers are adapted to engage with sliding frogs 38. These frogs may be employed to actuate the kick-off lever or brake devices or both. The frogs 38 may be of the type shown in Patent 1,322,605.

In the operation of the loom, the lay 10 is moved back and forth in the usual manner and the shuttle travels longitudinally of the lay and enters the shuttle boxes at the ends of its stroke. When the shuttle enters either shuttle box the lay will start on its forward stroke and complete the forward stroke. The shuttle will then hold the binder 14 in the outer position and the finger 26 will be pressed outwardly and the protector-rod 15 will be turned in opposition to its spring 27, whereby both daggers 37 will be raised so that they will not engage the sliding frogs. However, should the shuttle not enter either shuttle box, the binder would then not move outwardly and the finger 26 would remain in the inner position due to the turning movement of the binder shaft 15 caused by the spring 27 and the daggers 37 would remain lowered and would engage the sliding frogs 38 which would stop the action of the lay.

It frequently happens that the protector-rod breaks or becomes injured whereby the same must be removed for replacement or repair. An important feature of the present invention is the forming of the protector-rod in the outer end protector-rod sections and the intermediate protector-rod section. If either end protector-rod section is broken or damaged, the set screws 22 and 23 are loosened and the adjacent sleeve 21 is slid back upon the intermediate protector-rod section 17 thus disconnecting the coupling-sleeve 21 from the end protector-rod section 16. Then the bearing 18 is removed from the sword by unscrewing the single bolt 18' and this permits of the removal of the end protector-rod section 16 without disturbing the other end protector-rod section 16 or the intermediate protector-rod section 17. It is obvious that either end protector-rod section may be removed in this manner, replaced, and again rigidly connected with the intermediate protector-rod section 17. Should the intermediate protector-rod section 17 become broken or damaged it may be removed without disturbing the end protector-rod sections 16. This may be accomplished by unscrewing the set screws 22 and 23 of one coupling-sleeve 21, such as the coupling-sleeve 21 to the left, Figure 1, and the set screws 23 of the coupling-sleeve 21 to the right. The intermediate protector-rod section 17 is now shifted longitudinally to the right so that its left end is further spaced from the inner end 19 of the end protector-rod section 16 to the left and the intermediate protector-rod section 17 is now angularly adjusted so that its left free end and the left coupling-

sleeve 21 will pass the end 19 of the end protector-rod section 16 to the left. This is rendered possible by the fact that there is considerable clearance between the walls of the bearing 30 and the protector-rod section 17 and there is also considerable clearance between the wall of the coupling-sleeve 21 and the protector-rod section 17. The protector-rod section 17 may now be moved longitudinally and its removal effected, the spring being first disconnected from the bearing. The protector-rod section 17 may also be removed by sliding both coupling-sleeves 21 upon the same and removing the bolt 30', whereby the protector-rod section may be shifted laterally from its position. Further, if it should be desired to remove or replace the spring 27 it will not be necessary to remove the intermediate protector-rod section 17 or the end protector-rod sections 16. To accomplish this the set screws 22 and 23 of the coupling sleeve 21 to the right are unscrewed and the coupling sleeve 21 to the right is then slid inwardly upon the intermediate protector-rod section 17. The right end of the protector-rod section 17 is now shifted laterally so that the coupling-sleeve 21 will clear the adjacent right end protector-rod section 16 and may be slid off of the right end of the intermediate protector-rod section 17. The collar 34 may now be removed in a similar manner and then the spring 27. By a reverse operation the spring and collar 34 are returned to the intermediate protector-rod section, the coupling-sleeve 21 to the right again placed thereon, after which the intermediate protector-rod section 17 is brought into alignment with the right end protector-rod section 16 and the right coupling-sleeve again clamped to these parts by manipulation of the set screws 22 and 23. The intermediate protector-rod section is somewhat resilient and may be flexed for effecting these operations and there is some play in the bearing 30.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. In a protector mechanism for a loom having a lay, shuttle boxes, shuttle binders, swords and a frog, said mechanism comprising bearings mounted upon the swords, a protector-rod comprising end protector-rod sections journaled in the bearings and having fingers to engage the binders, an intermediate separate protector-rod section, coupling-sleeves substantially contacting with the inner ends of said bearings and receiving the ends of the end protector-rod sections and the intermediate protector-rod section, means to clamp the coupling-sleeves to the end protector-rod sections and the intermediate protector-rod section, and a dagger carried by the protector-rod to engage with the frog.

2. In a protector mechanism for a loom having a lay, swords, shuttle boxes, shuttle binders, a frog, and bearings mounted adjacent to the swords, a protector-rod comprising end protector-rod sections journaled in the bearings and having fingers to engage the binders, an intermediate separate protector-rod section, coupling-sleeves having their outer ends substantially contacting with said bearings and slidably receiving the ends of the end protector-rod sections and the inter-

mediate protector-rod section, means to detachably clamp the coupling-sleeves to the end protector-rod sections and the intermediate protector-rod section and holding the coupling-sleeves so that their outer ends substantially contact with the bearing, and a dagger carried by the protector-rod to engage the frog.

3. In a protector mechanism for a loom having a lay, shuttle boxes, shuttle binders, swords, bearings arranged adjacent to the swords and a frog, said mechanism comprising a protector-rod including end protector-rod sections journaled in the bearings and having fingers to engage the binders, an intermediate separate protector-rod section arranged between the inner ends of the end protector-rod sections and substantially shorter than the distance between such ends, coupling-sleeves having their outer ends substantially contacting with said bearings and slidably receiving the ends of the end protector-rod sections and the intermediate protector-rod section, means to clamp the coupling-sleeves to the end protector-rod sections and the intermediate protector-rod section, a bearing mounted upon the intermediate portion of the lay and receiving the intermediate protector-rod section, a collar mounted upon the intermediate protector-rod section, a spring carried by the intermediate protector-rod section and engaging the last named bearing and collar, and a dagger carried by the protector-rod to engage the frog.

4. A protector mechanism for a loom having a lay, shuttle boxes, shuttle binders upon the rear side of the lay, swords and a frog, said mechanism comprising bearings arranged beneath the lay and mounted upon the front side of the swords, a protector-rod comprising end protector-rod sections journaled in the bearings and having rearwardly projecting generally horizon-

tal extensions arranged beneath the lay which extensions are provided with upstanding fingers disposed upon the rear side of the lay and engaging the binders, an intermediate separate protector-rod section arranged between the ends of the end protector-rod sections and having a length substantially less than the distance between such ends, coupling-sleeves substantially contacting with said bearings and slidably receiving the ends of the end protector-rod sections and the intermediate protector-rod section, means to clamp the coupling-sleeves to the end protector-rod sections and the intermediate protector-rod section, a bearing mounted upon the lay and receiving the intermediate protector-rod section, a spring surrounding the intermediate protector-rod section and engaging the bearing, means to connect the spring with the intermediate protector-rod section, and a dagger carried by the protector-rod.

5. A protector mechanism for a loom having a lay and shuttle binders, a protector-rod mounted to travel with the lay, said protector-rod including end protector-rod sections and a separate intermediate protector-rod section, means for detachably connecting the end protector-rod sections and the intermediate protector-rod section, a bearing receiving the intermediate protector-rod section, a collar mounted upon the intermediate protector-rod section and having a part provided with openings, a spring surrounding the intermediate protector-rod section and having one end engaging the bearing and its opposite end inserted within a selected opening of the collar, means to clamp the collar in the selected adjusted position to the intermediate protector-rod section, and a dagger carried by the protector-rod.

GROVER C. TARTE.
